Primary Examiner — Derrick E Holland(74) *Attorney, Agent, or Firm* — Haynes and Boone, LLP(57) **CLAIM**

The ornamental design for a power control system, as shown and described.

DESCRIPTION

FIG. 1 is a front, left, and top perspective view of a power control system showing the new design;

FIG. 2 is a rear, left, and top perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the figures are shown for the purpose of illustrating portions of the power control system, optional accessories, and/or environmental matter and form no part of the claimed design.

1 Claim, 7 Drawing Sheets(56)
